UNITED STATES PATENT OFFICE

JOSEPH BRANDWOOD, OF MANCHESTER, ENGLAND

FLUID TREATMENT OF ARTIFICIAL-SILK THREADS OR FILAMENTS

Application filed August 2, 1928, Serial No. 297,022, and in Great Britain February 17, 1928.

Wound packages of artificial silk threads or filaments—hereinafter called threads—for instance in the form of a spun cake as they come from a spinning frame, cannot be satisfactorily treated with fluids under pressure, as the result of the pressure applied is to mat the threads together, and perfect desulphurizing, bleaching, dyeing, or other liquid treatment is out of the question by this method, whether the threads are in the form of a spun cake as aforesaid or in the form of a package of threads wound upon a bobbin as they come from the spinnerets, the form of wind of the threads being a close wind in each case without tension—as such term is understood in winding—on the threads.

The ordinary practice hitherto has been to reel the material into skeins from the cake or bobbin on which it has been spun, so that it might be put through the processes of washing, desulphurizing, bleaching dyeing and the like, as in skein form these treatments are possible and this reeling, with a subsequent stretching process applied to the hanks during drying, add to the strength, lustre and elasticity of the threads. To secure even treatment and to obtain this strength, lustre and elasticity, skeining has hitherto been unavoidable.

The object of the present invention is a means for treating a wound package of the threads in such a manner and in such a form that the matting together of the said threads shall be effectually prevented and easy and even penetration of the fluid be assured, whether such fluid is employed for washing, desulphurizing, bleaching, dyeing, drying or other operations.

The reeling of the threads into skeins with the subsequent stretching and handling of the material in skein form is thus avoided, with saving of labor costs and also saving the high degree of waste which is inherent in skeining such a fragile thread as an artificial silk thread. According to the said invention the threads are wound upon a tubular perforated or like spool with an open wind, which imparts a certain softness or resiliency to the wound package as a whole, as compared to a package as it comes from the spinning frame

or to a package which has been wound with a close or parallel wind, and the spool is then rotated around its axis at a speed sufficient to set up an appreciable centrifugal force within the package itself, fluid being at the same time applied to the spool interior.

Due to the open wind the centrifugal force as stated has a certain physical effect on the package which does not obtain with a closely wound package or a spun cake, this effect being a tendency to force the threads outwardly, thus keeping the interior of the package open for the ready passage of fluid therethrough and preventing matting of the threads. Fluid applied to the interior of the package passes, as a result of the rotation of the said package readily therethrough. The winding tension to be applied to the threads during the winding on process may be any convenient and it will, as will be understood, vary according to the precise nature and counts of the threads, and the wind itself must be such that unwinding to another form of wound package may take place when treatment is finished, whilst still leaving the package to be treated with a certain softness and resiliency which will allow it to be affected by centrifugal force as hereinbefore set forth. The wind may be a form of cross or like wind which will give the desired open wind result, the thread traverse guide in the winding machine being set to give a rapid traverse, in ratio to the winding on speed of the thread, for the purpose. The expression "open wind" where used in this specification and in the claims annexed thereto, is deemed to express this open wind with the desired softness and resiliency for the purpose of the invention, with consequent physical effect on the threads as a result of centrifugal force applied to them in that wound form.

The fluid when it is wash liquid or dye liquor may be applied to the inner face of the perforated spool in the form of a spray, or it may be applied in the form of a wide jet which, on impinging on the perforations of the rotating spool will be broken up. Also, as the effect of the open wind above indicated is to allow liquid to pass very rapidly through the wound package, for the best ef-

fect and for rapid treatment the liquid is applied to the inner face of the perforated spool along the whole length thereof. The liquid is supplied to the inner face of the spool in such volume that it is absorbed by the package as supplied thereto, forcing the liquid against the threads being thus entirely absent. The same effect is obtained if the volume of liquid supplied is less than that which the wound package as a package, in any given unit of time, is capable of absorbing. When a liquid is applied any portion of such liquid not immediately absorbed by the threads is radially ejected as a result of the centrifugal force.

As the absorption depends upon the speed of rotation and the centrifugal force thereby exerted on the thread mass itself in the package, the volume of fluid supplied will depend upon the speed of rotation. With a wound spool of about 6 inches overall diameter I find a rotative speed of about 1000-1300 revolutions per minute, with a suitable supply of fluid, very convenient.

Apparatus for carrying out the process may take various forms after the package has been wound as hereinbefore indicated with an open wind, so long as such apparatus allows of rotation of the package and its perforated spool holder with simultaneous supply of fluid to the interior of the spool. Such apparatus comprises therefore as its main features a rotatable holder on which a spool may be mounted with means for securing the spool to the holder to rotate the former; and a pipe passing within the spool for the supply of liquid.

The process with convenient apparatus for carrying it into effect will now be fully described, reference being had to the accompanying drawings which show apparatus for the fluid treatment. In the drawings:—

Figure 1 is a broken section of an apparatus for treating a plurality of wound spools mounted upon a perforated horizontal spindle.

Figure 2 is a section of the supporting and driving means for treating a single wound spool, in an apparatus as shown in

Figure 3 which illustrates an apparatus for separately treating a plurality of single wound spools and

Figures 4 and 5 are respectively a side elevation and a plan of the supporting means for a liquor supply pipe in the apparatus of Figure 3.

The manner of winding the package to be treated has already been indicated, for the purpose of forming said package so that it will be amenable to treatment whilst still having sufficient tension to retain its form as a package for subsequent unwinding. The necessary tension for the building of the package may be applied in any manner suitable, for instance by passing the thread to

the winding on point of its spool, over a stationary glass rod and a rotating glass rod, or either of them. Winding machines for the purpose are within the knowledge of those skilled in the art of winding threads and yarns of various fibres and need not be described or illustrated herein.

The perforated spool upon which the threads are wound may be of a light but strong material such as ebonite but it may be of a non-corrodible metal or alloy and be flanged. Preferably it is of large bore as compared to the thickness of thread mass wound thereon for the purposes of this invention, as if the thread mass is too thick the free exercise of the centrifugal force upon the said mass to produce the physical effect desired should be hampered. The spool itself forms per se no part of my invention.

Referring to the drawings, Figure 1, bearings 6, 7 are provided in which are fixed ball bearings 8 and 9 the spindle 10 rotatable in the ball bearings 9 and having keyed or otherwise secured thereon a pulley 11 which is driven from any suitable driving shaft. The spindle 12 is recessed at 13. The bearings 8 and 9 are mounted upon the walls of a tank 14, which may be provided with a hinged cover indicated in broken lines at 15.

A perforated tubular spindle 16 is provided upon which—the said spindle being removed from the apparatus—are mounted spools 17 with their wound packages α . A packing 18 is provided at each end, of ebonite, rubber or the like and when the desired number of perforated spools 17 is mounted on the tubular spindle 16 the whole is screwed up by the screw cap 19. In mounting the spools 17 on the spindle 16, care is taken that the solid part of the spindle shall not obturate perforations in a spool, and the perforations in the spindle 16 are therefore the same distance between centres as the perforations in a spool 17. The spindle thus being charged, it is fitted over the ball bearing 8 at one end on the bearing 6 its other end resting in the recess 13, a pin 20 being passed through a hole in the said spindle 16 and through holes in the sides of such recess 13.

From a suitable supply tank of liquid—with any known form of control and regulating valve or cock—not shown—a pipe is led to the interior of the tubular spindle 16 terminating in the pipe length 21 within such spindle. On the side adjacent to the inner faces of the perforated spools 17 this pipe length 21 is perforated with fine perforations, or it may be slotted along that length to allow of the ejection of a jet of fluid the length of such pipe but preferably narrow.

In operation, for instance for the washing of the packages, the pipe 21 is connected to a wash water tank. The valve being opened and the rotation of the spindle 16 being simultaneously started, water flows through

the orifices in the pipe 21, or through the jet therein, and impinges upon the inner face of the perforated spool, entering the perforations in the said face and passing by the centrifugal force exerted upon the spool and package, radially through the latter. This passage, due to the nature of the winding, of the thread package is extremely rapid and is in fact, with a suitable thickness of thread mass, practically instantaneous. Liquid absorbed within the package but unabsorbed by the threads thereof is thrown outwardly from the exterior of the package and collects in the tank in which the spindle is situated, being led away to drain or elsewhere.

For the treatment with dye liquor the process is exactly the same, as that above described, the pipe 21 being connected to a dye liquor vat, and dye liquor, unabsorbed by the threads, flowing from the treatment tank to a suitable collector.

Air may be admitted when desired with treatment liquid to assist the spray, or the jet as the case may be, and for this purpose a gravity flow from the liquid tank with an opening in the supply pipe for the admission of air may be provided. In practice however the spray or jet as above described is found satisfactory.

It will be seen that as the treatment with any liquid is the same, and as atmospheric air can be admitted to the tubular spindle 16, any desired sequence of operations, washing, air treatment, bleaching, etc., can be carried out without removing the spools 17 and their thread packages when once placed in the tank. The spindle 16 may if desired be reduced in length to take only one perforated spool 17 and its wound package α , with the end closers 18 and securing means.

When the treatment or any sequence of treatments is completed the spindle 16 is removed from the tank, and the spools removed therefrom for final drying by any suitable means as for instance in a drying chamber.

For treatment with gases, the latter may be admitted to the interior of the perforated tubular spindle 16 and be passed through the package by centrifugal force as described with reference to atmospheric air. Liquid and air, or liquid and gas, may if desired at any time be passed through together, as will be obvious from the description of the apparatus hereinbefore given.

Where it is desired to rotate a perforated spool and its wound package around a vertical axis the closing and securing means above described with reference to Figure 1 may be substituted by the apparatus shown in Figures 2, 3, 4, and 5 now to be described. In these figures the driving spindle 10 is vertical with a pulley 11 as before, and the fixed base 22 is provided within the tank 14 with a support 23 for a perforated spool 17 to which support the spool may be secured by spring

catches 24 fixed to such support and engaging a flange 25 of the spool. Ball bearings 26 and 27 are provided to allow of easy rotation of the spindle 10 and support 23 and these two members may be solid with each other or may be securable and detachable by means of a bayonet joint at 28. The end of the perforated spool may be closed by means of the rubber or analogous washer 29 on which it is seated, this washer being preferably permanently attached to a circular flange 29 of the support 23.

In this modification the removal of the spray or like pipe 21 is necessary to put a spool 17 into position or remove it. The supply pipe 30 from a liquid tank may therefore be flexible and be supported by the holder as shown in Figures 3 and 4.

Mounted upon the edge of the treatment tank 14 are the vertical rods 31 one opposite each spool position and a horizontal rail 32 is supported upon these vertical rods 31. Loosely mounted upon the said vertical rods 31 is a boss 33 to which is pivoted at 34 an arm 35 having a forked end 36 which supports the liquor supply pipe 21, being held in position by the screw 37. The whole thus forms a universally jointed arm which allows the pipe 21 held thereby to be moved over the spool and downwardly within it, and to be removed from the spool when desired.

To place the spool in position it is, after it has been wound, placed on the washer 29, the spring catches 24 yielding or being pressed outwardly to allow of this, and engaging the flange 25 of the spool as before explained by their spring pressure.

The pipe 21 is then swung up around, and downwardly to rest within the spool. Rotation of the latter and its package and simultaneous supply of liquid to the pipe 21 are then carried out exactly as before explained the flexible tube 30 being connected to any tank, or to a series of tanks in succession, for the supply of the necessary treatment liquid, and any air or other treatment being also given. When treatment is finished the operator lifts the pipe 21 out and moves it to its out of operation position; opens the spring catches 24 by means of thumb or finger projections thereon, and lifts the spool out, another being then placed in position.

The various parts of the apparatus may be of non-corrodible metal or be coated with such a metal, or be of ebonite or of the substance sold under the registered trade mark of "Bakelite", where desired, and as will be understood the details given may be varied so long as the desired degree of rotation with simultaneous supply of fluid to the interior of a perforated spool is assured.

I claim:—

1. A process for the treatment of artificial silk threads with fluids, consisting in winding the threads in a wound package upon a

tubular perforated spool with an open wind which will give a softness and resiliency to the package for the purpose set forth, rotating the spool and its borne wound package

5. at a high speed around its longitudinal axis, and simultaneously applying liquid to the inner face of the spool, this liquid being supplied to the spool per unit of time in a volume which is not greater than the volume of liquid
- 10 which may be absorbed by the package in the said time unit.

2. A process for the treatment of artificial silk threads with fluids, consisting in winding the threads in a wound package upon

- 15 a tubular perforated spool with an open wind which will give a softness and resiliency to the package for the purpose set forth, rotating the spool and its borne wound package at a high speed around its longitudinal axis,
- 20 and simultaneously applying liquid equally along the whole length of the inner face of the spool, this liquid being supplied to the spool per unit of time in a volume which is not greater than the volume of liquid which
- 25 may be absorbed by the package in the said time unit.

3. A process for the treatment of artificial silk threads with fluids, consisting in winding the threads in a wound package upon a

- 30 tubular perforated spool with an open wind which will give a softness and resiliency to the package for the purpose set forth, rotating the spool and its borne wound package at a high speed around its longitudinal axis, and
- 35 simultaneously applying liquid equally along the whole length of the inner face of the spool from a stationary tube around which the spool rotates, this liquid being supplied to the spool per unit of time in a volume which
- 40 is not greater than the volume of liquid which may be absorbed by the package in the said time unit.

In testimony whereof I have hereunto set my hand.

45

JOSEPH BRANDWOOD.
